UNITED STATES PATENT OFFICE.

DAVID W. MARTIN, OF PORTAGE, PENNSYLVANIA, ASSIGNOR OF ONE-HALF
TO GUSTAV H. R. GROKE, OF SAME PLACE.

NUT-LOCK.

SPECIFICATION forming part of Letters Patent No. 682,876, dated September 17, 1901.

Application filed August 8, 1901. Serial No. 71,349. (No model.)

To all whom it may concern:

Be it known that I, DAVID W. MARTIN, a citizen of the United States, residing at Portage, in the county of Cambria and State of Pennsylvania, have invented a new and useful Nut-Lock, of which the following is a specification.

This invention relates to nut-locks, and is designed to provide for locking a nut against accidental displacement by jarring movements and the like of the part to which the nut is applied and also to arrange for the convenient application and removal of the locking device without damage to the bolt and nut.

It is furthermore designed to provide a locking device which is complete in itself, so that it may be strong and durable and also inexpensively produced.

Another object resides in arranging for two forms of the device, one to lock a single nut and the other to lock a plurality of nuts without making any considerable change in the latter form of the invention.

A final object resides in providing for a co-operation between the locking device and the surface against which it is to lie, so as to prevent displacement of the device from the nut and to obviate turning thereof upon the bolt.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a perspective view illustrating the application of the present invention to lock a single nut. Fig. 2 is a sectional view taken in the direction of the bolt. Fig. 3 is a plan view of the blank from which the locking device is formed. Fig. 4 is a detail perspective view of the locking device. Fig. 5 is an elevation showing the invention applied to lock a plurality of nuts.

Fig. 6 is a detail perspective view of the latter form of locking-washer.

Like characters of reference designate corresponding parts in all the figures of the drawings.

Referring at first more particularly to Figs. 3 and 4 of the drawings, it will be seen that the present nut-locking washer embodies two members, designated, respectively, by the numerals 1 and 2, of which the member 1 forms the body portion and is somewhat larger than the member 2, which is adapted to be folded over across the back of the body portion along the line of connection between the two members, so that the respective openings 3 and 4 may register. The opening in the member 2 is preferably circular, so as to form a bolt-opening, while the opening 3 is somewhat larger and of polygonal shape, thereby to form a seat for the snug reception of a nut. The outer corners of the body portion are projected laterally, so as to provide locking wings or fingers 5, and said member is preferably bowed transversely, so as to give the required spring or elasticity to said wings or fingers. It will be understood that the washer is normally flat, and the members are bent or folded during the application of the device to a bolt and nut.

In applying the device, as best shown in Figs. 1 and 2 of the drawings, the member 2 is applied to the projected end of a bolt 6, after which the nut 7 is set tightly against said member and then the body portion 1 is bent over, preferably in a downward direction, until the nut is snugly seated in the opening or seat 3, and finally the corner wings or projections are snapped into suitable sockets or seats 8, produced in the plate or surface 9, against which the washer bears, said recesses being formed by a chisel or other implement just prior to the application of the washer to the bolt. It will now be observed that the member 2 is rigidly clamped between the nut and the part which carries the bolt, whereby the washer is held against displacement, and the spring projections are snapped into the sockets or seats, so as to prevent rotation of the washer and also to obviate outward displacement of the member 1 from the

nut, whereby the latter is effectually held against accidental turning upon the bolt by reason of jarring movements of the part to which it is applied. To unlock the nut, it is 5 merely necessary to force the spring fingers or projections 5 out of engagement with the seats in the surface 9, which operation may be conveniently performed by inserting any suitable implement between the outer bowed 10 free edge of the member 1 and the part 9 and then prying the member 1 outwardly to displace the projections from their engagement with the surface 9, and finally bending the member 1 so as to expose the nut, whereby 15 the latter is free, as may be readily understood.

To accommodate the device to a plurality of adjacent nuts—as, for instance, in a rail-joint—the member 1 is extended to any suitable 20 length, as indicated in Figs. 5 and 6, and is provided with a plurality of polygonal openings or seats 3. Instead of having a single member 2 extended for the entire length of the member 1, I prefer to employ two such 25 members 2, having the usual bolt-openings, so as to receive a pair of bolts in the manner described for the first form of the device. The outer corners of the member 1 have the locking projections 5, as in the first form, and 30 it is apparent that both forms of the invention are applied in substantially the same manner.

From the foregoing description it will be noted that the only difference between the 35 two forms resides in providing one of the forms with a single nut-receiving seat or opening and providing the other form with a plurality of such seats, and also in providing the modified form with terminal bolt-receiving members, so as to obviate a long single member, and thereby materially reduce the 40 weight of the washer.

The present device is designed to be formed from such strong sheet metal as is capable of 45 being bent or folded in applying and removing the device and also which is capable of being bowed to give the required elasticity to the nut-engaging member in order that the locking projections may be sprung into locked 50 engagement with the part that carries the bolt and also maintained in effective engagement therewith.

What I claim is—

1. A nut-lock comprising opposite members 55 which are foldably connected and provided

with corresponding openings, one of which openings is polygonal in shape and also larger than the other, the member having the polygonal opening being provided with means to coöperate with the surface against which it is 60 to lie and have an interlocked engagement therewith to prevent separation of the members.

2. A nut-lock comprising opposite members which are foldably connected and also provided with corresponding openings, one of which openings is polygonal in shape, and the member having the polygonal opening being provided at opposite sides with lateral locking 65 projections.

3. A nut-locking washer formed from a single blank of metal and having opposite members which are capable of being folded over toward each other, and also provided with openings which are constructed to register 75 when the members are folded, one of said openings being polygonal in shape, and the member having the polygonal opening being provided at its outer corners with lateral locking 80 projections.

4. The combination with a member having a bolt-opening, a bolt projected through the opening, and a nut applied to the projected end of the bolt, of a nut-locking washer having a part which is provided with a bolt-opening and is located between the member and the nut, and also having a locking part which is folded over toward the first-mentioned part and is provided with a polygonal opening or seat snugly receiving the nut, the outer corners of this latter part being provided with spring projections that are snapped into sockets or seats formed in the adjacent surface of the member which carries the bolt.

5. A nut-locking washer consisting of a 95 plate which is folded to form opposite members, said members being provided with registered openings, one of which openings is polygonal in shape, the member which has the polygonal opening being provided with lateral corner projections, and said member also being bowed intermediately of the projections to give elasticity thereto.

In testimony that I claim the foregoing as my own I have hereto affixed my signature in 105 the presence of two witnesses.

DAVID W. MARTIN.
